FIG. 1 is a top perspective view of a pair of end caps for a curtain rod in accordance with a preferred embodiment of my design;

FIG. 2 is a top plan view thereof;

FIG. 3 is a bottom plan view thereof;

FIG. 4 is a rear elevational view thereof;

FIG. 5 is a front elevation view thereof;

FIG. 6 is a left side elevational view thereof;

FIG. 7 is a right side elevational view thereof; and,

FIG. 8 is a greatly enlarged perspective view of an endcap of the pair of end caps for a curtain rod in accordance with the preferred embodiment of my design.

The broken lines in the figures are to illustrate environmental structure only and form no part of the claimed design.
